UNITED STATES PATENT OFFICE.

RUEL E. DEWEY, OF GRAND RAPIDS, MICHIGAN.

TRIPPLICATE VACUUM AND AIR TRAP.

1,171,599.

Specification of Letters Patent. Patented Feb. 15, 1916.

Application filed March 12, 1915. Serial No. 14,035.

To all whom it may concern:

Be it known that I, RUEL E. DEWEY, a citizen of the United States of America, residing at Grand Rapids, in the county of Kent and State of Michigan, have invented certain new and useful Improvements in Triplicate Vacuum and Air Traps; and I do hereby declare the following to be a full, clear, and exact description of the invention, such as will enable others skilled in the art to which it appertains to make and use the same.

This invention relates to a triplicate vacuum and air trap adapted to be used with vapor heating systems.

It is a primary object and purpose of the invention to provide a device of this character which may be applied to a vapor vacuum heating system, in use permitting the ready escape of air from the radiators and connecting pipes of the system, and at the same time insuring against the escape of the heat carrying vapor or of hot water from the system and also against the entrance of air into the system through said device.

In vapor heating systems the collection of air in radiators and connecting pipes or mains is very objectionable and it is desirable that this air be removed from the system as quickly as possible. Furthermore it is essential that the heat carrying vapor, such as steam or the like, be held within the radiators and pipes of the system and not permitted to escape and, when the system is cooling, after having been supplied with the heat carrying vapor, it is essential that the vacuum produced by the cooling shall not draw in air. My apparatus is designed to attain all these ends and to work substantially automatically, requiring practically no attention and being substantially proof against getting out of order.

The construction embodying my invention is disclosed in the accompanying drawings, in which:

Figure 1 illustrates a heating system equipped with my invention. Fig. 2 is a vertical sectional view taken through the air and vacuum valve portion of the device. Fig. 3 is a similar view taken through the float chamber; and Fig. 4 is a horizontal section on the line 4-4 of Fig. 3.

Like reference characters refer to like parts throughout the several views of the drawings.

In the heating system shown, a heater of

any approved type such as shown at 1 is used to generate the heat carrying vapor such as steam or water vapor which is carried through the supply mains 2, the excess over and above that required to supply the radiators and the condensation that takes place in the mains 2 being returned through the pipe 3 to the lower portion of the heater 1 as shown. Branches 4 extending from the length of the mains 2 at any desired points serve to conduct the heat carrying vapor to radiators 5, the return therefrom being through return pipes 6 which also lead to the lower part of the heater, the usual check valve 6^a being interposed between the heater and the return pipes to insure against a flow of hot water from the heater in a backward direction through the return pipes. The construction thus described is common and well known in heating systems and is disclosed chiefly for the purpose of illustrating the use and operation of my invention in connection therewith.

In the mains 2 a short distance from the heater 1 a union 7 may be located from which leads a pipe 8 of comparatively small diameter, its end threading into the lower member 9 of an air and vacuum valve control which is comprised of the two curved members 9 and 10 having interposed between them a diaphragm 11, preferably of rubber, though any suitable flexible material may be used. The inclosure formed by member 9 and diaphragm 11 is steam tight but member 10 has a plurality of openings 10^a whereby the pressure on the upper side of the diaphragm is that of the outside atmosphere. A short connecting pipe 12 leads from and is carried by the upper member 10 threading at its upper end into the valve casing 13. A valve 14 of the usual construction is located in the casing and adapted to close the passageway therein when seated against its valve seat. An outlet 15 is provided to the valve casing and in diametrically opposed relation, a conducting pipe 16 is connected to the valve casing adapted to carry the air, as will be hereinafter explained, from the heating system to the casing 13. The valve 14 is connected by a rod 17 with diaphragm 11, any suitable form of permanent connection being used. It will be apparent that when the pressure of vapor in the mains 2 rises slightly above that of ordinary atmospheric pressure, the vapor entering through pipe 8

presses against diaphragm 11 and serves to elevate the valve 14 above its seat so that air may have free passage through pipe 16, casing 13 and the outlet 15. But if at any time the pressure in the mains 2 falls below that of the atmosphere, diaphragm 11 is forced downwardly and draws the valve 14 into close contact with its seat, shutting off any flow of air through the valve casing 13. By reason of the comparatively large diameter of the diaphragm but very slight variations in pressure above or below atmospheric pressure are required to operate the valve away from or tightly against its seat. In the return pipe 6 a T-union 18 is shown to which the screw threaded end 19 of a base member 20 of a float chamber is connected. The chamber is completed by the housing member 21 which on its upper side has a screw threaded lug 22 joined by a suitable coupling with the pipe 16 heretofore described. Parts 19 and 22 are bored to permit the free passage of air from the return pipes 6 to the pipe 16. Within the housing 21 a float 23 is located which consists of a shell-like construction, within which is placed any suitable dilating fluid adapted to expand readily at temperatures below that of steam. The float 23 has a lower extension 24 seating into the projection 20^a of the base 20 and at its upper end is provided with a valve 25 which is normally located slightly below a valve seat 26 formed at the lower end of the passageway 35 through the projection 22. A tube 27 is located in the float chamber, its upper end extending nearly to the top thereof while its lower end passes into the portion 20^a, the extension 24 to the float being of a formation permitting the passage of the tube 27 as shown in Fig. 4.

The operation of the construction shown is as follows: As soon as a heat carrying vapor has been generated and introduced in the main 2 and the pressure thereof becomes slightly more than the outside pressure of the atmosphere, valve 14 is raised above its seat. As the vapor circulates any air in the radiators and in the pipes or mains of the system is forced ahead of the vapor through float chamber 21 and the pipe 16 and thence outwardly through the pipe 15. If, however, after the air has been expelled, steam attempts to pass through the float chamber the fluid contained within the float 23 expands sufficiently to press the valve 25 against the seat 26 closing the passage to pipe 16; also if from any cause hot water should be introduced into the chamber the float 23 is elevated and the passageway closed by valve 25 before any water can escape. The apparatus therefore permits the ready escape of air from the heating system but serves as an effectual bar to the escape of water or vapor. While

the heater is supplying a heating fluid to the system the pressure in the radiators and pipes is above that of the outside atmosphere and valve 14 is held in upper position. On cooling, condensation takes place in the system and the pressure therein falls below that of the outside atmosphere. Thereupon valve 14 immediately closes and is held very firmly in closed position, barring the entrance of air into the heating system from the outside. If water at any time enters the float chamber 21 it readily drains off, the pipe 27 permitting an equalization of pressure above and below the water contained in the chamber as will be readily understood.

The construction thus described consists of few parts and is very efficient in practical operation. By its use air from a heating system is expelled very rapidly with no back pressure and none of the annoyance ordinarily caused by the presence of air in the system will be observed.

Changes in minor detail may be resorted to without departing from the invention which is defined in the appended claims and all modifications falling within the scope of said claims are to be considered as comprehended within my invention.

I claim:

1. In a device of the character described, a valve casing, a valve located therein, an outlet to the casing, a rod connected to the valve extending downwardly therefrom, a flexible diaphragm secured to the lower end of the rod, a support for the diaphragm connected with and positioned below the valve casing, a member in said support forming with the diaphragm a tight inclosure, an inlet pipe to the inclosure, a pipe leading into the valve casing, a float chamber joined with the inlet pipe, a float containing a dilating fluid, a valve on the float, and a valve seat a short distance above the valve formed at the entrance of the passageway from the chamber to the float, substantially as described.

2. In a device of the character described, a valve casing, inlet and outlet pipes connected thereto, a valve in the casing, a member connected to the casing containing a tight inclosure having a flexible side, an inlet pipe leading into the inclosure, a rod connecting the valve and flexible side, a float chamber connected with the inlet pipe to the valve casing with an outlet passage from the interior of the chamber to the pipe, an inlet to the float chamber, a hollow float filled with a dilating fluid in the chamber, and a valve carried by the float adjacent the entrance of the outlet passage, substantially as described.

3. In a device of the character described, a valve casing, inlet and outlet pipes connected thereto, a valve in the casing, an

inclosure having a flexible side, a pipe leading into the inclosure, connections between the valve and the flexible side of the inclosure whereby the valve moves with said side, a chamber connected with the inlet pipe with a passage from the chamber to the valve casing normally open, and a thermostatic device within the chamber having means to close the passage upon rise of the temperature in the chamber above a predetermined degree.

4. In a device of the character described, a valve casing, an inlet pipe connected thereto, a valve in the casing, an inclosure having a flexible side secured to the casing, a pipe leading into the inclosure, a rod connecting the valve and flexible side of the inclosure, a float chamber connected with the inlet pipe with a passage from the chamber to the valve casing normally open, and a combined float and thermostatic regulator having means to close the passage either by elevation of the float on entrance of water into the float chamber or by expansion of the float on entrance of vapor having a temperature above a predetermined degree.

5. In a vapor heating system a supply main to conduct heat carrying vapor to radiators in the system, a return main to conduct the condensation, vapor and air from the radiators, a device including a float chamber connected to the return main, a valve casing containing a valve, connections between the valve casing and float chamber providing a passageway from the return main through the float chamber to the valve casing, and means in the float chamber permitting the free passage of air through the float chamber but acting to close the passage therefrom on attempted passage of water or heat carrying vapor, substantially as described.

6. In a vapor heating system, a supply main to conduct heat carrying vapor to radiators in the system, a return main to conduct condensation, vapor and air from the radiators, a valve casing, a valve therein, an inclosure having a flexible side, a pipe

leading from the supply main into the inclosure, a rod connected at its ends to the valve and flexible side, a chamber secured to the return main, connections between the chamber and valve casing whereby a passage normally open is provided from the return main to the valve casing, and a device in the float having means to close the passage on entrance of water or heat carrying vapor into the chamber but inoperative on entrance of air therein.

7. In a vapor heating system, supply and return mains, means to expel air from the system including a valve, means to place the valve in opened or closed positions through pressure from the supply mains or atmospheric pressure as the pressure in the supply main rises above or falls below atmospheric pressure, respectively, a conduit in which the valve is located connected with the return main, and means interposed in the conduit permitting the free passage of air from the return main but closing the conduit against the passage of water or heat carrying vapor, substantially as described.

8. In combination, a valve casing having an outlet, a valve therein, an inclosure having a flexible side, a pipe leading from the inclosure adapted to connect with the supply main in a vapor heating system, a rod connected at its ends to the valve and the flexible side of the inclosure, a chamber adapted to be connected to the return main of the vapor heating system, connections between the chamber and valve casing forming a passageway therebetween, and a device in the chamber having means to close the passageway between the chamber and valve casing on entrance of water or heat carrying vapor into the chamber but inoperative on entrance of air therein.

In testimony whereof I affix my signature in presence of two witnesses.

RUEL E. DEWEY.
